ATTORNEY

UNITED STATES PATENT OFFICE.

HENRY DE CORTE, OF FAIRGROVE, MICHIGAN.

TORPEDO-GUARD.

1,243,143.

Specification of Letters Patent.

Patented Oct. 16, 1917.

Application filed January 26, 1917. Serial No. 144,710.

To all whom it may concern:

Be it known that I, HENRY DE CORTE, a citizen of the United States, residing at Fairgrov, in the county of Tuscola and

5 State of Michigan, have invented certain new and useful Improvements in Torpedo-Guards, of which the following is a specification.

10 My invention relates to improvements in torpedo guards, and it consists in the constructions and arrangements herein described and claimed.

15 An object of my invention is to provide a shield or guard, applicable to vessels and fortified places, the device being constructed in units which may be placed to ward off attacks from aerial torpedoes as well as submarine torpedoes.

20 Other objects and advantages will appear 25 from the following specification reference being had to the accompanying drawing in which:

Figure 1 is a side elevation illustrating diagrammatically a portion of a vessel showing the application of my device, and

Fig. 2 is a cross section on the line 2—2 of Fig. 1, a portion of the complete structure being broken away.

30 In carrying out my invention I provide companion guard members 1 and 2. The member 1 of which there is one on each side of the vessel (the guard member 1 being adapted more particularly for attachment to a vessel), is supported on the sides of 35 the vessel 3 by suitable hook members 4 and 5.

35 The hook members 4 and 5 are arranged to be supported in brackets 6 secured to the side of the vessel. Arranged centrally and 40 longitudinally of the guard member 1, is a series of brace members 7 including diverging arms 8 which are secured in any suitable manner to the body of the shield 1, similarly as are the hook members 4 and 5.

45 The end of the brace 7 adjacent the side of the vessel 3, is turned downwardly into a hook 9 which is supported in the bracket 10 also secured to the side of the vessel 3 similarly as are the brackets 6. It will be 50 observed that the guard or shield 1 is formed with gradual outwardly converging top and bottom portions. The lower curve of the guard member 1 merges substantially with the lower curve 11 of the vessel. The purpose 55 of this construction will readily be apparent. A torpedo in being directed to the

vessel 3 will strike the guard 1 on the lower concave surface thereof and be directed downwardly in the direction of the arrow and away from the vessel.

60

The purpose of the hook connections 4 and 5 as well as the hook connection of 9 of the brace 7, is to facilitate the removal of one or both of the guards 1 for such purposes as docking the vessel, and permitting it to move up to a wharf. It should also be stated that the guards 1 are applied to the vessel so that the outer point thereof forming the terminus of the converging side portions, is located just about at the water 70 line.

Reference is now directed to the guard 2. The guard 2 is similar in its general aspects, to the guard 1. The guard 2 is supported on the deck of the vessel by the members 12, 75 of which there is a sufficient number to properly support the guard in position. The body of the guard 2 is formed with outwardly diverging side members, which spring from the upper central point 13. 80

It will be seen that the sides of the upper guard 2 terminate at a point 14 approximately in the region where the inner sides of the guards 1 end. The vessel being attacked from overhead, and a torpedo being 85 dropped on the vessel, will strike the outwardly diverging sides of the guards 2, and be caused to be deflected outwardly in the direction of the arrow and away from the vessel. Should the torpedo be misdirected 90 and fail to strike either of the surfaces of the guard 2, and should it strike the upper surface of the guard 1, the torpedo will still be deflected outwardly and into the water where it can do no harm to the vessel. 95

By reference to Fig. 1, it will be seen, that the front ends of the guards 1 terminate in an outwardly converging portion 15. This portion of the guard will probably extend across the bow and stern of the vessel in a 100 formation similar to that of the main body of the guard 1. Torpedoes being directed to either the bow or stern of the vessel from either above or below, will be directed outwardly or downwardly as the case may be. 105

The same holds true to the guard 2, since it will be observed that the adjacent end of the guard 2 is also outwardly curved as at 16.

While the construction of the device is 110 illustrated largely diagrammatically in the drawing, yet it is that of a generally pre-

ferred form, and obviously in actual practice various modifications and changes may be made without departing from the spirit of the invention or scope of the claims.

5 I claim:

1. In a device of the character described, the combination with the deck and sides of a vessel, of covering shields for the sides, the shields having surfaces diverging toward 10 the sides, a covering shield for the deck, said shield having surfaces diverging toward the sides of the vessel, the upper edges of the side shields ending near the lower edges of the deck shields to form a substantial continuation of the deck shield, whereupon a projectile will be caused to deflect from one shield to the other and away from the vessel.
- 15 2. In a device of the character described, the combination with a vessel, a shield applied to the sides of the vessel and having 20

portions extending across the bow and stern thereof, the shield having concave outwardly converging surfaces, the lower surfaces merging with the hull of the vessel and the upper surfaces ending at the juncture of the 25 sides and deck of the vessel, a second guard supported on the deck of the vessel comprising concave and outwardly diverging sides, said sides ending at the region adjacent the point of connection of the side 30 guards with the deck of the vessel said side guards forming a continuation of the upper guard, and means for removably supporting the guards in position.

In testimony whereof I affix my signature 35 in presence of two witnesses.

HENRY DE CORTE.
